US0D1077916S

(12) United States Design Patent (10) Patent No.: US D1,077,916 S
(45) Date of Patent:  Jun. 3, 2025

(54) GAMING MACHINE(71) Applicant: Aristocrat Technologies Australia Pty Limited, North Ryde (AU)(72) Inventors: Ariel Turgel, San Francisco, CA (US); Daniel Harden, Palo Alto, CA (US); Cheng-Fu Hsieh, Sunnyvale, CA (US); Bruce Urban, Las Vegas, NV (US); Dominic DeMarco, Round Rock, TX (US); Timothy Barbour, Nolensville, TN (US); Ryan Priddy, Franklin, TN (US); William Lamb, Eagleville, TN (US); Raquell Verri, Franklin, TN (US); Ryan Slaybaugh, Nashville, TN (US); James Vicain, Allen, TX (US)(73) Assignee: Aristocrat Technologies Australia Pty Limited, North Ryde (AU)() Term: 15 Years(21) Appl. No.: 29/861,526(22) Filed: Nov. 30, 2022*Related U.S. Application Data

(60) Division of application No. 29/696,682, filed on Jun. 28, 2019, now Pat. No. Des. 978,246, which is a continuation of application No. 29/658,892, filed on Aug. 3, 2018, now Pat. No. Des. 917,621.
